UNITED STATES PATENT OFFICE.

MAX KOPS, OF RIVERDALE, NEW YORK, ASSIGNOR TO KOPS BROS. INC., A CORPORATION OF NEW YORK.

ELASTIC WEBBING.

Application filed May 31, 1924. Serial No. 715,799.

To all whom it may concern:

Be it known that I, MAX KOPS, a citizen of the United States, residing at Riverdale, in the county of Westchester and State of New York, have invented an Improvement 5 in Elastic Webbing, of which the following is a specification.

My present invention relates to elastic webbing or similar structures adapted particularly for use in corsets and other similar garments, for hose supporters, although as will be understood the invention is not so limited. The invention furthermore relates to that form of elastic webbing in which there is provided an elastic section and an 10 inelastic section, the inelastic section being provided in order that the webbing may be connected at the inelastic section to a corset or other garment in such a manner that the elasticity of the webbing is not injured in 15 making this connection. Elastic webbings of this particular type have been made heretofore by crowding the warp and weft threads in the webbing or otherwise binding the elastic straps in the inelastic sections of 20 the webbing in such a manner that the needle carrying the thread for securing the webbing to the garment has no material effect in the elastic portion thereof.

In carrying out my present invention the 25 webbing made in accordance therewith comprises a plurality of strips of elastic fabric each comprising a base of rubber or other similar elastic material and a face or covering of yielding fabric such for example as knitted silk which is vulcanized or otherwise secured thereto so as to become an integral part thereof. These strips of elastic material initially are elastic throughout 30 their entire length. In predetermined sections of the webbing I employ a liner or intermediate member between the strips of elastic material and these strips of material with the section or sections of inelastic material are superposed and connected at their edges by lines of stitching or otherwise so

that when completed the sections in which the linings of inelastic material are placed are made inelastic thereby, while the other sections of the webbing retain their elastic characteristics, as will be hereinafter more 50 particularly described.

In the drawing:

Fig. 1 is a plan of a section of elastic webbing made in accordance with my invention.

Fig. 2 is a longitudinal section on line 55 2—2, Fig. 1 made on an enlarged scale to more clearly illustrate the construction, and

Fig. 3 is a partial plan illustrating the use of the invention as applied to a corset 60 or other similar apparel garment.

Referring to the drawing, and particularly to Figs. 1 and 2, in carrying out this invention the elastic webbing made in accordance therewith comprises a plurality of strips of elastic fabric. As illustrated, I have shown two of these strips which are indicated at *a* and *b* respectively, although as will be understood any number of these strips of material may be employed. These strips are placed together and connected to each other and to an intermediate or liner member in such a manner as to provide an inelastic section *c* and an elastic section *d* in the webbing, it being understood that these elastic and inelastic sections alternate 65 with each other throughout the entire length of the webbing, although as illustrated but one elastic and one inelastic section are shown. The strips of elastic material are similarly constructed. For example the 70 strip *a* consists of a body of elastic material such as sheet rubber 10 or other material equally impervious to moisture and oppositely disposed layers of fabric, such for example as knitted silk as indicated at 11 and 12. These layers of the fabric are 75 preferably vulcanized to the rubber or other elastic base. The strip *b* is similarly constructed and comprises a base 13 of sheet rubber or similar material and layers 14 and 15 of knitted silk or other and equivalent

fabric. In predetermined sections between these strips of elastic material I provide a liner or intermediate member as indicated at 16. This intermediate member is of predetermined length depending upon the length which it is desired to make the inelastic sections of the webbing. These parts, namely the strips *a* and *b* and the liner or intermediate member 16 are superposed and their edges connected by suitable stitches 17 and 18 which, for example, may be the generally known overlock stitch. With the parts thus assembled and connected the webbing is complete and ready for use.

In Fig. 3, for example, I have illustrated the use of the webbing in an apparel corset. In this figure 19 indicates a portion of the lower section of the body or the skirt member of an apparel corset. To this section of the corset adjacent the lower edge thereof the inelastic section *c* of the webbing is connected by suitable lines of stitching 20 or otherwise. As is customary the elastic section of the webbing *d* is fitted with a buckle 21 and a clasp 22 to engage the hose. The buckle as will be understood as is also customary may be adjusted to position on the elastic section of the webbing to make the hose supporter the desired length to apply sufficient tension to the hose to maintain the same in position.

I claim as my invention:

1. An elastic webbing having an elastic section and an inelastic section composed of strips of material each comprising an elastic sheet and a fabric secured thereto, an inelastic fabric member in the inelastic section of the webbing, and lines of stitching connecting the edges of the said strips of material and the said inelastic fabric member.

2. An elastic webbing having an elastic section and an inelastic section composed of strips of material each comprising a sheet of rubber and a fabric secured thereto, an inelastic fabric member in the inelastic section of the webbing, and lines of stitching for connecting the edges of the said strips of material and the said inelastic fabric member.

3. An elastic webbing having an elastic section and an inelastic section composed of strips of material each comprising an elastic member and a knitted silk fabric secured thereto, an inelastic member in the inelastic section of the webbing, and lines of stitching for connecting the edges of the said strips of material and the said inelastic member.

4. An elastic webbing having an elastic section and an inelastic section composed of strips of material each comprising a sheet of rubber and a knitted silk fabric secured thereto, an inelastic fabric member in the inelastic section of the webbing, and lines

of stitching connecting the edges of the said strips of material and the said inelastic fabric member.

5. An elastic webbing having an elastic section and an inelastic section composed of strips of material each comprising an elastic sheet and layers of fabric secured to both sides thereof, an inelastic fabric member in the inelastic section of the webbing, and stitches connecting the edges of the strips of material and the said inelastic fabric member.

6. An elastic webbing having an elastic section and an inelastic section composed of strips of material each comprising a sheet of rubber and layers of knitted silk fabric secured to both sides thereof, an inelastic fabric member in the inelastic section of the webbing, and stitches connecting the edges of the strips of material and the said inelastic fabric member.

7. An elastic webbing having an elastic section and an inelastic section composed of strips of material each comprising an elastic sheet and a fabric vulcanized thereto, an inelastic fabric member in the inelastic section of the webbing, and stitches connecting the edges of the strips of material and the said inelastic fabric member.

8. An elastic webbing having an elastic section and an inelastic section composed of strips of material each comprising a sheet of rubber and a fabric vulcanized thereto, an inelastic fabric member in the inelastic section of the webbing, and stitches connecting the edges of the strips of material and the said inelastic fabric member.

9. An elastic webbing having an elastic section and an inelastic section composed of strips of material each comprising a sheet of rubber and a knitted silk fabric vulcanized thereto, an inelastic fabric member in the inelastic section of the webbing, and stitches connecting the edges of the strips of material and the said inelastic fabric member.

10. An elastic webbing having an elastic section and an inelastic section composed of strips of material each comprising an elastic sheet and a layer of fabric vulcanized to both sides thereof, an inelastic fabric member in the inelastic section of the webbing, and stitches connecting the edges of the strips of material and the said inelastic fabric member.

11. An elastic webbing having an elastic section and an inelastic section composed of strips of material each comprising a sheet of rubber and a layer of fabric vulcanized to both sides thereof, an inelastic fabric member in the inelastic section of the webbing, and stitches connecting the edges of the strips of material and the said inelastic fabric member.

12. An elastic webbing having an elastic

section and an inelastic section composed of strips of material each comprising an elastic sheet and a knitted silk fabric vulcanized to both sides thereof, an inelastic fabric member in the inelastic section of the webbing, and stitches connecting the edges of the strips of material and the said inelastic fabric member.

13. An elastic webbing having an elastic section and an inelastic section composed of

strips of material each comprising a sheet of rubber and a layer of knitted silk fabric vulcanized to both sides thereof, an inelastic fabric member in the inelastic section of the webbing, and stitches connecting the edges of the strips of material and the said inelastic fabric member.

Signed by me this 22nd day of May, 1924.

MAX KOPS.
